UNITED STATES PATENT OFFICE.

THOMAS C. WELCH, OF CHICAGO, ILLINOIS.

AUTOMATIC STRIPPING AND TIPPING DEVICE.

1,315,888.

Specification of Letters Patent.

Patented Sept. 9, 1919.

Application filed June 5, 1915. Serial No. 32,428.

To all whom it may concern:

Be it known that I, THOMAS C. WELCH, a citizen of the United States, residing at Chicago, in the county of Cook and State of Illinois, have invented certain new and useful Improvements in Automatic Stripping and Tipping Devices, of which the following is a description.

My invention relates to that general class of devices employed in binding books and especially to means for attaching the end sheets to the end sections.

The object of my invention is to produce a simple, convenient, reliable and rapid device of the kind adapted to automatically paste and attach the end sheets to the end sections, thus entirely avoiding the slow and inaccurate hand work for all kinds of work that may be required in this portion of the binding operations.

To this end my invention consists in the novel construction, arrangement and combination of parts herein shown and described, and more particularly pointed out in the claims.

In the accompanying drawings wherein like or similar reference characters indicate like or corresponding parts:

Figure 1 is a side elevation of one end of my device with parts removed and broken away to more clearly show the construction.

Fig. 2 is a plan view of the part of my device shown in Fig. 1.

Fig. 3 is a detail of a slightly modified form of mechanism for detaching the sections from the feeding pins of my device.

In the form shown my device comprises a receiving table 1 provided with suitable guides 2 and 3 for accurately controlling the lateral position of the sections on the table and preventing their displacement when being operated upon.

An auxiliary table 4 is provided slightly above, and substantially parallel to the table 1, so that a section may be placed upon the table 1 and suitable end sheets may be placed upon the auxiliary table 4 and held substantially parallel to and directly above the several sections on the table 1. The width of the auxiliary table 4 is slightly less than the operative portion of the table 1 so that a portion of the section and of the end sheets will project beyond the edge of the auxiliary table and may be pasted together if desired without pasting the remaining surfaces of the adjacent sheets.

The guides 2 and 3 may be rigidly held in position in any desired manner. As shown the guide 2 is rigidly secured in position near one edge of the table 1 and the guide 3 is adjustably mounted upon the table 1 substantially parallel to the guide 2 by suitable screws 5—5 or other convenient means extending through the brackets 6—6 upon the guide and engaging the table 1 thus securely clamping the brackets to the table. The distance between the guides 2 and 3 is obviously controlled by the width of the section which it is desired to operate upon.

The auxiliary table 4 is preferably of suitable width to accomodate the narrowest section which it is desired to handle in my device and consists merely of a strip of steel or other suitable material rigidly connected by a bracket 7 to a paste reservoir 8 or other convenient part of the mechanism which is in turn provided with the rod 9 rigidly attached thereto and arranged to coöperate with a bracket 10 upon the table 1 to rigidly secure the reservoir in position to permit of its vertical adjustment as desired.

In the preferred construction the auxiliary table is suitably spaced from the guide 2 and a paste distributing wheel 11 projects through the bottom of the reservoir 8. The lower edge of the distributing wheel 11 extends into the spaces between the auxiliary table 4 and guide 2 in position to contact with any sections positioned between the guides and passing between the table 1 and auxiliary table 4.

In the preferred construction the distributing wheel 11 is rigidly mounted upon a shaft 12 which is in turn rotatably mounted in suitable bearings 14—14 upon the reservoir 8 with a sheave 15 rigidly attached to the shaft and connected by a belt 16 or other suitable means to a drive sheave 17 for rotating the distributing wheel.

Any suitable means may be provided for feeding the book section along the table 1. In the form shown a groove 18 is provided extending longitudinally of the table 1 intermediate the guides 2 and 3 in close proximity to the edge of the auxiliary table 4 opposite the guide 2. A pair of sprocket wheels 19 and 20 are rotatably mounted near the opposite ends of the table 1 arranged to support a chain or other flexible connector 21 between them with the upper portion of the chain positioned in the groove 18. The sheave 19 is rigidly mounted upon a shaft 22 rotatably supported in bearings 23 near

its opposite ends. The sprocket wheel 20 is rigidly mounted upon a shaft 24 rotatably mounted in suitable bearings 25—25 upon the table 1. One end of the shaft 24 projects beyond the side of the table adjacent the guide 2 and the sheave 17 is rigidly secured to this projecting portion of the shaft. In the preferred construction suitable pins or other convenient means are provided at 10 suitable intervals in the chain 21 to receive a book section between them so that when the shaft 24 is rotated the several book sections will be engaged by the pins and carried longitudinally of the table under the distributing wheel 11 and the auxiliary table 4. The pins 26 may be of any suitable form or construction and attached to the chain 21 in any suitable manner. In the form shown the pins 26 are each provided with a threaded 20 portion adapted to engage a threaded opening in suitable portions of the chain 21 so that the several pins may be spaced at any desired intervals upon the chain and rigidly held in their adjusted position. Each of the 25 pins is of sufficient length to extend above the upper surface of the auxiliary table 4 and engage any end sheets or sections positioned upon the auxiliary table, thereby moving them longitudinally of the auxiliary 30 table immediately above the sections upon the table 1 with the rear end of the sections or sheets upon the two tables substantially in line with each other vertically.

Suitable means are preferably provided 35 for forcing the sheets or sections on the auxiliary table into contact with the pasted portions with the sections on the main table. In the preferred construction a bracket 28 is provided upon the table 1 projecting above 40 the guide 2. An arm 29 having a rotatable roller 30 at its free end is pivotally attached to the upper end of the bracket 28 so that the roller 30 will rest upon the sheets passing from the auxiliary table 4 and press the same 45 downward upon the pasted portion of the sections on the main table.

Suitable means are also provided to disengage the sections from the pins 26 at the sprocket wheel 20. In the form shown in 50 Fig. 1 a plurality of fingers 84 are rigidly secured to the sprocket wheel 20 in such a position that as the wheel rotates the several fingers will successively protrude above the surface of the table 1 and each will engage 55 and raise the rear end of a section above the adjacent pin 26.

In the form shown in Fig. 3 the fingers 84 on the sprocket wheel 20 are dispensed with and an arm 87 having an upwardly projecting portion 88 at its free end is rigidly attached to a shaft 89 which is rotatably mounted below the table 1. An arm 91 is also attached to the shaft 89 and a bar 90 extends from the free end of the arm 91 to a 60 point near the end of the roller 35. Suit-

able means are provided on the bar 90 to engage a portion of the roll 35 or other convenient means adjacent thereto to prevent vertical movement of the free end of the bar 90 without interfering with its longitudinal 70 movement. A roller 92 is also provided near the free end of the bar 90 adjacent the roller 35 and a cam 93 is rigidly connected to the roller 35 and adapted to engage the roller 92 to periodically oscillate the bar 90 longitudinally and thereby partially rotate the shaft 89. When this occurs the part 88 of the finger 87 moves upward through a suitable slot in the table 1 and engages the rear 80 end of the book section on the table and forces the same upward sufficiently to clear the pins 26. The several parts are so proportioned and arranged that the movement of the finger 87 accurately corresponds with the spacing of the pins 26 so that the part 88 85 passes upward through the slot in the table 1 just before each of the pins 26 reaches the part 88.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. In a device of the kind described, a main table, and an auxiliary table positioned directly above said main table, in combination with guides extending longitudinally and common to both of said tables and feeding mechanism for moving articles along each of said tables and maintaining an article on said auxiliary table directly above an article on said main table.

2. In a device of the kind described, a main table, and an auxiliary table positioned directly above and substantially parallel to said table, in combination with a fixed guide extending longitudinally of and common to both of said tables and feeding mechanism for moving articles along each of said tables and maintaining an article on said auxiliary table directly above an article on said main table.

3. In a device of the kind described, a main table and an auxiliary table positioned directly above said main table and in close proximity thereto, in combination with side guides extending longitudinally of and common to both of said tables, and feeding mechanism for moving articles along each of said tables and maintaining an article on said auxiliary table directly above an article on said main table.

4. In a device of the kind described, a main table, and an auxiliary table positioned directly above said main table, in combination with fixed guides extending

- longitudinally and common to both of said tables and feeding mechanism for moving articles along each of said tables and maintaining an article on said auxiliary table 5 directly above an article on said main table.
5. In a device of the kind described, a main table, and an auxiliary table positioned directly above said main table, in combination with guides mounted upon said 10 main table extending longitudinally of and common to both of said tables and feeding mechanism for moving articles along each of said tables and maintaining an article on said auxiliary table directly above an article 15 on said main table.
6. In a device of the kind described, a main table, and an auxiliary table positioned directly above said main table, in combination with side guides extending 20 longitudinally and common to both of said tables and feeding mechanism mounted upon said main table for moving articles along each of said tables and maintaining an article on said auxiliary table directly above 25 an article on said main table.
7. In a device of the kind described, a main table, and an auxiliary table positioned directly above said main table, in combination with side guides extending longitudinally and common to both of said tables and feeding mechanism comprising sprocket 30 wheels rotatably mounted upon said main table, a flexible member connecting said sprockets and a plurality of pins upon said 35 flexible connector extending above the face of said auxiliary table for moving articles along each of said tables and maintaining an article on said auxiliary table directly above an article on said main table.
- 40 8. In a device of the kind described, a main table, and an auxiliary table positioned directly above said main table, in combination with guides extending longitudinally and common to both of said tables 45 and feeding mechanism for moving articles along each of said tables and maintaining an article on said auxiliary table directly above an article on said main table and means for coating a part of the upper surface of the objects on said main table with an adhesive material.
- 50 9. In a device of the kind described, a main table, and an auxiliary table positioned directly above and substantially parallel to said main table and in close proximity thereto, in combination with a fixed guide 55 extending longitudinally of and common to both of said tables and feeding mechanism for moving articles along each of said tables 60 and maintaining an article on said auxiliary table directly above an article on said main table.
- 65 10. In a device of the kind described, a main table, and an auxiliary table positioned directly above and substantially parallel to 70 said main table, and in close proximity thereto, in combination with a fixed guide common to both of said tables and feeding mechanism for moving articles along each of said tables and maintaining an article on 75 said auxiliary table directly above an article on said table.
11. In a device of the kind described, a main table, and an auxiliary table positioned directly above and substantially parallel to said main table, and in close proximity thereto, in combination with a fixed guide mounted upon said main table extending longitudinally of and common to both of said tables and feeding mechanism for 80 moving articles along each of said tables and maintaining an article on said auxiliary table directly above an article on said main table.
12. In a device of the kind described, a main table and an auxiliary table positioned directly above and substantially parallel to said main table, and in close proximity thereto, in combination with a fixed guide mounted upon said main table extending 85 longitudinally of and common to both of said tables and feeding mechanism mounted upon said main table for moving articles along each of said tables and maintaining an article on said auxiliary table directly 90 above an article on said main table.
13. In a device of the kind described, a main table, and an auxiliary table positioned directly above and substantially parallel to said main table, and in close proximity thereto, in combination with a fixed guide mounted upon said main table extending 95 longitudinally of and common to both of said tables and feeding mechanism mounted upon said main table comprising sprocket 100 wheels rotatably mounted upon said table, a flexible member connecting said sprockets and a plurality of pins upon said flexible connector extending above the face of said auxiliary table for moving articles along 105 each of said tables and maintaining an article on said auxiliary table directly above an article on said main table.
14. In a device of the kind described, a main table, and an auxiliary table positioned directly above said main table, and in close proximity thereto, in combination with a guide 110 extending longitudinally of and mounted upon said main table common to both tables and feeding mechanism mounted upon said main table, comprising sprocket wheels rotatably mounted upon said table, a flexible member connecting said sprockets and a plurality of pins upon said flexible connector extending above the face of said auxiliary table for moving articles along 115 each of said tables and maintaining an article on said auxiliary table directly above an article on said main table and means for coating a part of the upper surface of the objects on said main table with an adhesive material.

objects on said main table with an adhesive material.

15. In a device of the kind described, a main table, and an auxiliary table positioned 5 directly above said main table, and in close proximity thereto, in combination with a guide extending longitudinally of and mounted upon said main table common to both of said tables and feeding mechanism 10 comprising sprocket wheels rotatably mounted upon said main table, a flexible member connecting said sprockets and a plurality of pins upon said flexible connector extending above the face of said auxiliary 15 table for moving articles along each of said tables and maintaining an article on said auxiliary table directly above an article on said main table means for coating a part of the upper surface of the objects on said 20 main table with an adhesive material and means for forcing a part of each object from said auxiliary and said main tables into contact adjacent said guide.

16. In a device of the kind described, a 25 main table, and an auxiliary table positioned directly above said main table and in close proximity thereto, in combination with a guide extending longitudinally of and mounted upon said main table common to 30 both of said tables and feeding mechanism

for moving articles along each of said tables and maintaining an article on said auxiliary table directly above an article on said main table means for coating a part of the upper surface of the objects on said main table 35 with an adhesive material and means for forcing a part of each object from said tables into contact at said coated part.

17. In a device of the kind described, a main table, and an auxiliary table positioned directly above said main table, in combination with a guide extending longitudinally and common to both of said tables and feeding mechanism for moving articles 40 along each of said tables and maintaining 45 an article on said auxiliary table directly above an article on said main table, means for coating a part of the upper surface of the objects on said main table with an adhesive material, and means for forcing a 50 part of each object from said auxiliary and said main tables into contact adjacent said guide.

In testimony whereof, I have hereunto signed my name in the presence of two 55 subscribing witnesses.

THOMAS C. WELCH.
